5 Claims. (Cl. 250—27)

My invention relates to electron discharge tubes having indirectly heated cathodes, more particularly to means for decreasing the initial heating period required to bring the cathode to full emitting temperature.

In the usual electron discharge tube having an indirectly heated cathode, a heating element or heater is provided for heating the electron emitting layer or coating on the cathode, and is electrically insulated from this layer or coating. The emitting layer or coating is heated from the heater element either by thermal radiation or preferably by thermal conduction, to the working temperature required for the emission of electrons. In this latter instance, the cathode support consists, for example, of a tube made from some ceramic material which supports on the outside upon a suitably prepared metallic intermediate layer or sleeve, an electron-emissive coating, while the heater element is placed within the ceramic tube. Inasmuch as the ceramic material means an increase of the mass to be heated, the initial heating period will be increased; in other words, the time which it takes the cathode to attain the working temperature after the heating current has been switched on is increased over the filament type of cathodes. The initial heating time for a given mass of ceramic material to be heated in a cathode will be longer the smaller the heating power used for the operation of the cathode. The indirectly heated cathodes of the usual construction require about one minute of heating before their full electron emission has been attained. This relatively long heating period is very undesirable particularly in broadcast receivers. Hence, it is not only desirable to decrease the initial heating or starting period where the heating power source is limited, but it is also desirable to diminish the heating or starting period which has heretofore been regarded as unavoidable. The arrangement described below is of particular importance in the case of cathodes having a heating power of 3 watts and less.

45 The principal object of my invention is to provide means for decreasing the heating period required for bringing an indirectly heated cathode of an electron discharge device to full emitting temperature.

50 In accordance with my invention, the indirectly heated cathode is provided with a heater composed of several resistor elements or groups of resistor elements. During normal operation these resistor elements are all connected in series.

55 If the number of elements is n , and if the re-

sistance of an element is R in terms of ohms, and the heating voltage available is E in volts, then the energy developed in the heater body will be:

$$\frac{E^2}{n \cdot R} \text{ watts}$$

In accordance with my invention the resistor elements are arranged so that they may be connected in parallel during the starting or initial heating period. Inasmuch as the effective resistance of n parallel elements each of R ohms, is equal to

$$\frac{R}{n}$$

ohms, the energy consumed by the heater in terms of watts will be equal to

$$\frac{n \cdot E^2}{R}$$

It can be seen therefore that with the parallel connection, the consumption of power has been increased by the factor n^2 . As a consequence the initial heating period will thus be reduced to a fraction of its normal or original value. It has been found to be sufficient to make the heater of two resistor elements, in which case a four-fold increase in heating energy will be obtained when the heaters are connected in parallel.

The parallel connection should be maintained only for a period of time required to bring the cathode to its working temperature. In a simple arrangement this change from the parallel connection to the series connection of the resistor elements could be manually effected by the operator or user of the set, though this would require attention in order that undue overloading of the cathode would not result in the destruction of the same. Hence, it is desirable to accomplish the change in the circuit connection automatically as soon as the requisite electron emission has been obtained. For example, a time relay could be provided which, after a predetermined length of time, which could be determined experimentally and which as a rule would amount to only fractions of a second, would effect the change in the circuit. However, the switching device could be also made to depend for its operation upon the electron emission current proper by inserting a relay in the external circuit of an electrode carrying direct current, for example, the anode or the screen grid. The relay could be arranged to initiate the change in the connection as soon as the current flowing thru the

relay winding has attained a predetermined value. In order to avoid the necessity for using an unduly sensitive type of relay, the relay could also be inserted in a circuit common to several tubes, for example, the anode circuit.

The novel features which I believe to be characteristic of my invention are set forth with particularity in the appended claims, but the invention itself will best be understood by reference 10 to the following description taken in connection with the accompanying drawing in which: Figure 1 is a diagrammatic representation of a circuit arrangement embodying my invention. Figures 2 and 3 are diagrammatic representations of 15 modifications of portions of the arrangement shown in Figure 1.

Referring to the drawing, an electron tube 10 is provided with a plate 11, a control electrode 12 and an indirectly heated cathode 13. The cathode heater comprises two resistor heater elements 14 and 15 which are provided with three supply leads 16, 17 and 18. The heating voltage is furnished from the secondary winding 19 of a heating transformer 20. The plate circuit which 25 includes the plate voltage supply or source AB, in addition to the output transformer 21, includes electromagnetic means such as a relay having a winding 22 and armature 24 for changing the connections of the cathode heater elements 14 30 and 15. The armature 24 of the relay is mounted on a pivot 23 and is biased by the action of a spring 25 into the position shown in the drawing. The armature is provided with two conducting segments 26 and 28 insulated from each other. 35 The relay winding 22 is suitably by-passed for alternating current by means of condensers 27. In the case of radio sets operated directly from the supply lines, the relay winding could be replaced by a filter choke or else the latter could 40 be provided additionally. The segment 26 in the position shown in the drawing (which may be regarded as the starting position) and which corresponds to a time at which there is very little or no plate current, closes the contacts a, b, while 45 the segment 28 closes the contacts c, d. The two resistor elements 14 and 16 under these conditions are connected in parallel across the secondary 19 of transformer 20. As soon as the plate current has attained a predetermined magnitude, 50 the relay armature 24 will be attracted by the winding 22 and moved into the position indicated by the dotted lines, and will be retained in this position as long as the set is in operation. This action opens contacts a, b and c, d, the contact 55 segment 26 then closing the contacts e, f to provide a series connection of the resistor elements 16 and 14. As a result the consumption of power is reduced to one-fourth of the power consumption 60 during the parallel connection.

60 The contact construction of the relay may take any number of forms well known in the prior art; for example, they may be of the pot or tank type. Furthermore, the change in the circuit could be effected by means of any well known 65 type of time-switch instead of the relay. The time-switch, for example, could be operated by means of a spring motor which could be wound up by manually operated means upon switching on the receiving set. Thermostatically operated 70 switch relays, including, for example, a bimetal strip acting as the regulatory means may be used in place of the relay shown, the bimetal strip being responsive to a predetermined temperature of the tube itself or of a series resistance. This 75 series resistance may, for example, be a safety

lamp of miniature size or an iron-hydrogen resistor, thru which a current flows, the current being proportional to the cathode temperature.

A thermostatically operated means for actuating the switch arm 24 is shown in Figure 2. The switch arm 24 has connected to it a link 31 biased to close the series contacts by means of spring 32 and is provided with a catch 33 for engaging latch 34 connected to the thermostatic element 35 for holding switch 24 in position to make the 10 parallel connections. The thermostatic element is responsive to the heat generated by the heater resistor 36 substituted in the anode circuit for the electromagnetic coil 22. This resistor element is heated by the current flowing in the anode 15 circuit. When the cathode has reached its full emitting temperature and normal current flows in the anode circuit thru resistor 36, sufficient heat is developed to cause the thermostatic element 35 to move to the position indicated in 20 dotted lines to release latch 32 whereby switch 24 moves with a snap action to change the parallel connection of the cathode heater elements to a series connection.

In the modification shown in Figure 3 a spring 25 motor is depended upon to automatically change the parallel connection of the cathode heaters to a series connection. In this arrangement the latch 34 is provided with a dash pot 37 for regulating the rate of movement of the latch when 30 actuated by means of springs connected to the latch and the switch 38. Upon closing the switch 38 the springs 39 are placed under tension and tend to move the latch 34 away from the catch on the link 31. The dash pot is so regulated that 35 the latch is released when the cathode has reached full emitting temperature, the switch 24 then being moved to its right hand position to open the parallel connection and close the 40 series connection of the cathode heaters. In this last arrangement the electromagnetic coil 22 of the relay may be replaced with the choke 48 in the anode circuit.

While I have indicated the preferred embodiments of my invention of which I am now aware 45 and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

55 What I claim to be new is:—

1. An electron discharge tube having an anode, an indirectly heated cathode, a pair of resistor heating elements for said cathode, circuits for said resistor heating elements, switching means associated with said circuits and movable to one position for connecting the resistor elements in series and movable to another position for connecting said resistor heating elements in parallel, and means responsive to the emission current of said cathode for operating the switch.

60 2. An electron discharge tube having an indirectly heated cathode and a plurality of other electrodes, a pair of heater elements for said cathode, circuits for said heater elements, switching means associated with said circuits and movable to one position for connecting the heater elements in series and movable to another position for connecting the heater elements in parallel, and means responsive to the current flow-

- ing in one of said other electrodes for operating said switch.
3. An electron discharge tube having an anode and an indirectly heated cathode, a circuit connected to said anode, a pair of heater elements for said cathode, circuits associated with the heater elements, a switch associated with said circuits and movable to one position for connecting the heater elements in series and movable to another position for connecting the heater elements in parallel, and an electromagnetic relay for operating said switch having an actuating winding connected as a choke coil in the circuit connected to the anode of said electron discharge tube.
4. An electron discharge tube having an anode and an indirectly heated cathode, a circuit con-

nected to said anode, a plurality of resistor heating elements for said cathode and switching means for connecting the resistor elements in series or in parallel, and a bi-metallic strip responsive to the heating action of the current flowing in the circuit connected to said anode for operating said switch.

5. An electron discharge tube having an anode and an indirectly heated cathode, a circuit connected to said anode, a plurality of heater elements for said cathode and switching means for connecting the heater elements in series or in parallel, a resistor in the circuit connected to said anode and a bi-metallic strip responsive to the temperature of said resistor for actuating said switching means.

HORST ROTHE.
